UNITED STATES PATENT OFFICE

JEROME P. BYRON, OF LYNN, AND ANDREW R. RIDDERSTROM, OF NAHANT, MASSACHUSETTS, ASSIGNEES, BY MESNE ASSIGNMENTS, TO UNITED SHOE MACHINERY CORPORATION, OF PATERSON, NEW JERSEY, A CORPORATION OF NEW JERSEY

FOLDING MACHINE AND METHOD

Application filed April 9, 1921. Serial No. 459,894.

The present invention relates to folding methods and machines, and more particularly to methods of and machines for folding a binding strip around the edge of a boot or 5 shoe upper to which it is attached.

The object of the present invention is to provide an improved method of the above-described character and an improved machine particularly adapted for use in carrying out the improved method.

In the drawings, Fig. 1 is a side elevation, partly in vertical section along the line 1—1 of Fig. 3, looking in the direction of the arrows, of a machine constructed according to a 15 preferred embodiment of the present invention; Fig. 2 is a section taken along the line 2—2 of Fig. 1, looking in the direction of the arrows; Fig. 3 is a front elevation, partly in vertical section along the line 3—3 of Fig. 1, 20 looking in the direction of the arrows; Fig. 4 is a horizontal section, taken upon the line 4—4 of Fig. 1, looking in the direction of the arrows; Figs. 5 to 8 inclusive are views showing successively assumed positions of portions of the mechanisms shown more particularly in Fig. 1; and Fig. 9 is a view corresponding to Fig. 7, showing certain parts enlarged for clearness.

The present invention will be hereinafter 30 described in connection with the folding of a binding strip 402, Figs. 5 to 8, of cloth, silk and the like, around the edge 404 of a sheet of leather or other material 406, such as a boot or shoe upper, to which it is attached.

35 The attaching is usually effected by sewing an edge 408 of the strip to a face 410 of the shoe upper, along the edge 404, so that the sheet and the strip extend at an angle to each other from the secured-together edges 404 and 408.

40 The stitches are shown at 412. The angle between the sheet and the strip is usually small, the sheet and the strip extending generally in more or less close parallelism, but the angle may be quite large. The particular article 45 described above is chosen herein for illustrative purposes only, in order to fix the ideas, and the invention is not limited to operation upon any specific article.

50 In practicing the invention, the shoe upper is placed with the face 410 resting upon

a platform or support 424. The unsecured or free edge 426 of the strip 402 is initially moved by hand into the space between two gripper jaws 12 and 432. The machine being then set into operation, successive portions 55 of the unsecured edge 426 of the strip 402 are intermittently gripped by the gripper jaws and pulled across the secured-together edges 404 and 408, and folded tightly around these edges, in the direction of the arrow, Fig. 7. 60 It is very important that the strip be pulled very tightly and folded while held tightly. The folded portions are intermittently advanced by a feed mechanism to fold-presser 4 of well-known type that intermittently 65 presses down the folded portions into even contact with the face 416 of the sheet, Fig. 8. The binding strip is caused to adhere to the sheet by cement. These operations are continued alternately in timed relation to each 70 other, until the whole strip has been folded.

The machine shown in the accompanying drawings for the purpose of illustrating the invention is modelled somewhat after a well-known machine disclosed in the patent to Diehl, No. 733,170, July 7, 1903, but suitably modified to adapt it to the carrying out of the method of the present invention, and reference is made to the said patent for a fuller 75 description of such details as are not more fully described or illustrated herein, because not particularly related to this invention. The same reference characters are employed in the present drawings to indicate parts that correspond more or less closely to those shown in the patent. The base 1 of the machine is shown provided with an overhanging arm 2 in the forward portion of which is fitted a vertically reciprocating fold-presser bar 3 carrying the fold presser 4 and actuated by the usual crank-and-pitman connection with the forward end of the rock-shaft 5 having upon its rear end the crank pin 6, connected by the pitman 7 with a crank pin 8, mounted between the balance wheel 9 and the rotary main shaft 10. The feed point 442, of well-known construction, co-operates with the usual four-way feed block 441. The feed block 441 is driven by an old and frequently 80 employed mechanism that is shown partly 85

90 95 100

by full lines and partly by dotted lines in Fig. 3. The usual gage 434 is employed to guide the stock, and it is positioned so that the binding strip shall be engaged by the edge of the platform or support 424 and the unsecured edge of the strip maintained separated from the sheet, as is illustrated more particularly in Figs. 1 and 5, to enable the gripper jaws 12 and 432 to secure a good grip thereon.

The gripper jaws 12 and 432 are mounted to oscillate in a plane oblique to the fold-presser 4. The gripper jaw 12 is fixed upon one end of a slightly inclined rock-shaft 13, disposed substantially parallel with the line of feed and mounted in suitable bearings in a swinging frame or carrier 14, pivoted upon centers 15, so as to reciprocate thereon transversely of the line of the feed, the shaft 13 having upon its opposite end a crank 16, carrying a pin 17 loosely fitted to rock within a slide block 18. The said end of the shaft 13 is bent slightly out of line with the body of the shaft, as shown in Fig. 3, to permit the gripper jaws 12 and 432 to operate in nearly a vertical plane. The reciprocating frame or carrier 14 is connected, intermediate its pivotal bearings and the rock-shaft 13 mounted thereon, by means of a link 19, to the shorter arm 20 of a substantially right-angled bell-crank lever whose other and longer arm 21 is connected by a link 22 to a forked lever 23, pivoted upon the frame or carrier 14. The slide block 18 is adapted to be reciprocated between the prongs of the forked lever 23 to effect the actuation of the crank 16. The bell crank 20, 21 is fixed upon the outer end of a short intermediate shaft 24, mounted in suitable transverse bearings in the base of the machine and having upon its inner end a lateral crank-arm 25, deriving a vibrating motion from a pitman 26, connected therewith at one end by a ball-joint and at the opposite end embracing a ball-crank 27 upon the main shaft 10. As indicated in the drawings, the several rock-shafts and pivotal pins of the train of mechanism intermediate the shaft and the pitman 26 are disposed in lines parallel with the shaft.

By reference to Fig. 1 it will be observed that the bell-crank or rocker 20, 21 is so disposed upon its supporting rock-shaft 24 that in the lower position of the gripper jaws, illustrated in Figs. 1 and 5, both the arms 20 and 21 are substantially above the axis of the rock-shaft and, in the motions to and from such position, actuate the parts connected with the links 19 and 22 at nearly equal speeds; but as said bell-crank approaches the full-line position indicated in Fig. 1 of the above-named patent and in Fig. 7 of the present drawings, the shorter arm 20 maintains its substantially uniform speed of movement, while the longer arm 21 nearly crosses the center of oscillation, thus

producing a differential speed of motion of the reciprocating members 19 and 22, and therefore of the carrier 14 and forked lever 23; the arrested crank pin 17, in conjunction with the more quickly moving carrier 14 of its shaft 13, serving to turn the gripper jaws into the position indicated in Fig. 7. The mechanism for communicating to the gripper jaws and to their carrier their respective motions thus comprises the common actuating device, consisting of the bell-crank or rocker 20, 21 and the intermediate bodily reciprocating link members 19 and 22, attached to the latter by direct pivotal connections.

The gripper jaw 432 is automatically actuated by the gripper jaw 12 through a gear 444 that is pivotally mounted at 446 upon the gripper jaw 12 so as to rock thereon, and that meshes with a gear 448 that is fixed to the jaw 432, and that is similarly rockably mounted upon the gripper jaw 12 at 450. Rocking movement of the gear 444 is thus communicated to the gear 448 and, therefore, to the gripper jaw 432 to which the latter is fixed. The gear 444 is automatically rocked back and forth by a rack bar 452 that meshes with the gear 444 and that is slidably mounted in a holder 454. As the gripper jaw 12 is oscillated back and forth by its above-described actuating mechanism, it causes the rack bar to reciprocate in the holder 454, this reciprocation causing the rocking of the gears 444 and 448 and, therefore, the alternate opening and closing of the gripper jaws.

As the gear 444 does not travel along a straight line, it is necessary, in order that the rack bar 452 may be maintained in mesh therewith, not only that the rack bar reciprocate, but that it be capable also of transverse movement. In the specific embodiment of the invention that is herein illustrated and described, the rack bar and its holder 454 are both permitted to oscillate transversely. To this end, the holder 454 is pivotally mounted about a stud 456 that is secured to a depending bracket 458. A coil spring 460 tends to maintain the holder 454 so as to hold the rack bar in mesh with the gear 444, but the spring yields to permit the rack bar being forced outward transversely in the direction of the arrow, Fig. 8, during the return movement of the gripper jaws after they have released their hold upon the binding strip.

In order that the rack bar shall not bind in the holder 454, the opening 462, Fig. 2, through which the rack bar slides is made greater than the thickness of the bar at its intermediate reduced portion 464. The face of the rack bar at 464 is made flat so that it may be engaged by a bearing plate 466. The bearing plate is maintained pressed flat against the flat face of the rack bar by a

spring-pressed plunger 468. The pressure of the spring 470 upon the plunger 468 may be adjusted by a thumb screw 472. By this construction, the rack bar is held tightly in the holder 454, but is prevented from binding thereagainst during its reciprocation.

By reference to Figs. 5 to 8, inclusive, it will be seen that the unfolded portions of the strip are gripped by the grippers while the 10 angle included between such portions and that face of the sheet to which the strip is attached is less than one hundred and eighty degrees, and are then folded around the secured-together edges and pressed against 15 the other face of the sheet. As shown, the sheet is horizontal and unfolded portions of the strip are extending downwardly when they are gripped.

The invention has been described herein 20 as embodied in a special machine of well known type, because leading to clearness of understanding and brevity of description, without confusing the essential novelty of the invention. It will be understood, however, that the invention itself is not restricted 25 to any particular machine, and that modifications may be made by persons skilled in the art without departing from the spirit of the invention as defined in the appended 30 claims.

What is claimed as new is:

1. A machine of the class described having, in combination, two gripper jaws, means for actuating one of the jaws, a gear pivoted upon said jaw, a gear meshing with the first-named gear fixed upon the other jaw, and a gear meshing with the pivoted gear movable upon the actuation of the said first-named jaw to effect the movement of the pivoted 40 gear and, through the latter, of the second-named gear.

2. A machine for folding a strip around the edge of a sheet of material to one face of which, along said edge, an edge of the 45 strip is secured so that the strip and the sheet extend from the secured-together edges at an angle to each other, said machine having, in combination, a support upon which the sheet is adapted to rest, a gage for guiding the sheet positioned so that the strip shall be engaged by the edge of the support, and means for gripping the edge-engaged 50 strip and moving it across the secured-together edges.

3. A machine of the class described having, in combination, two gripper jaws, means for actuating one of the jaws along a curved path, a gear pivoted upon said jaw, a gear meshing with the first-named gear fixed upon the other jaw, a rack bar meshing with the 60 pivoted gear movable upon the actuation of the said first-named jaw to effect the movement of the pivoted gear and, through the latter, of the second-named gear, a movable holder in which the rack bar is adapted to

slide and means whereby the rack bar is held tightly in the holder.

4. A machine for folding a strip around the edge of a sheet of material to one face of which, along said edge, an edge of the 70 strip is secured so that the strip and the sheet extend from the secured-together edges at an angle to each other, the said machine having, in combination, means for feeding the sheet, means for engaging the strip to 75 maintain the unsecured edge of the strip separated from the sheet while the sheet is fed, and means for gripping the unsecured edge of the strip and moving it across the secured-together edges. 80

5. The method of folding a strip around the edge of a sheet of material to one face of which, along the said edge, an edge of the strip is secured so that the sheet and the strip extend from the secured-together edges at an angle to each other, a ridge being adapted to be formed at the junction between the sheet and the strip by the folding of the strip around the edge of the sheet, the said method comprising supporting the 90 sheet upon a support having an edge with the ridge projecting beyond the said edge of the support, and folding the strip around the secured-together edges. 95

6. A machine for folding a strip around the edge of a sheet of material to one face of which, along the said edge, the strip is secured, there being a ridge at the junction between the sheet and the strip, the 100 said machine having, in combination, a support having an edge, the sheet being adapted to be supported upon the support with the ridge projecting beyond the said edge of the support, means for folding the strip around the secured-together edges and means 105 for feeding the sheet and the strip with the sheet supported upon the support and the ridge projecting beyond the said edge of the support. 110

7. A machine for folding a strip around the edge of a sheet of material to one face of which, along the said edge, an edge of the strip is secured, there being a ridge at the junction between the sheet and the strip, the said machine having, in combination, a support having an edge, the sheet being adapted to be supported upon the support with the ridge projecting beyond the said edge of the support, and means for folding the strip around the secured-together edges, 115 pressing the folded portions of the strip and feeding the sheet and the strip with the sheet supported upon the support and the ridge projecting beyond the said edge of the support. 120

8. A machine for folding a strip around the edge of a sheet of material to one face of which, along the said edge, the strip is secured, there being a ridge at the junction 130 between the sheet and the strip, the said ma-

chine having, in combination, means for folding the strip around the secured-together edges, a support having an edge, the sheet being adapted to be supported upon the support with the ridge projecting beyond the said edge of the support, and means cooperating with the support for pressing the strip against the other face of the sheet.

9. The method of folding a strip around the edge of a sheet of material to one face of which, along the said edge, the strip is secured, there being a ridge at the junction between the sheet and the strip, the said method comprising supporting the sheet upon a support having an edge with the ridge engaging the said edge of the support and projecting beyond the said edge of the support, folding the strip around the said edge of the sheet, and pressing the strip against the other face of the sheet.

10. A machine for folding a strip around the edge of a sheet of material to one face of which, along the said edge, the strip is secured, there being a ridge at the junction between the sheet and the strip, the said machine having, in combination, a support having an edge upon which the sheet is adapted to rest with the ridge engaging the said edge of the support and projecting beyond the said edge of the support, and means for folding the strip around the said edge of the sheet.

11. The method of folding a strip around the edge of a sheet of material to one face of which along the edge an edge of the strip is secured so that the sheet and the strip extend from the secured-together edges at an angle to each other, the said method comprising gripping the strip while it is in a position in which the angle included between it and that face of the sheet material to which the strip is attached is less than one hundred and eighty degrees, folding the strip around the secured-together edges, and pressing the strip into contact with the other face of the sheet.

12. The method of folding a strip around the edge of a sheet of material to one face of which along the edge an edge of the strip is secured so that the sheet and the strip extend from the secured-together edges at an angle to each other, the said method comprising gripping the strip while it is in a position in which the angle included between it and that face of the sheet to which the strip is attached is less than one hundred and eighty degrees, pulling it across and around the secured-together edges and pressing it against the other face of the sheet.

13. A machine for folding a strip around the edge of a sheet of material to one face of which along said edge an edge of the strip is secured so that the strip and the sheet extend from the secured-together edges at an angle to each other, said machine having, in combination, two gripper jaws adapted to grip

intermittently successive portions of the strip while the angle included between said portions and that face of the material to which the strip is attached is less than one hundred and eighty degrees and fold them around the secured-together edges, a fold presser for intermittently pressing the folded portions, and means for operating the gripper jaws and the fold presser.

14. A machine for folding a strip around the edge of a sheet of material to one face of which along said edge an edge of the strip is secured so that the strip and the sheet extend from the secured-together edges at an angle to each other, said machine having, in combination, means for intermittently feeding the sheet, means for gripping successively advanced portions of the strip while the angle included between said portions and that face of the sheet to which the strip is attached is less than one hundred and eighty degrees, and for folding said portions around the secured-together edges during pauses in the feed, and means for pressing the successively folded portions into contact with the other face of the sheet.

15. A machine for folding a strip around the edge of a sheet of material to one face of which along said edge an edge of the strip is secured so that the strip and the sheet extend from the secured-together edges at an angle to each other, said machine having, in combination, a support for the sheet, means for feeding the sheet over the support with the strip extending downward, means for gripping downwardly extending portions of the strip and folding them around the secured-together edges, and means for pressing them against the upper face of the sheet.

16. A machine for folding a strip over the edge of a sheet of material to one face of which, along said edge, an edge of the strip is secured so that the strip and the sheet extend from the secured-together edges at an angle to each other, said machine having, in combination, two gripper jaws adapted to grip intermittently successive portions of the strip and fold them about said edges, means for operating one gripper jaw from the other, a fold-presser, and means for actuating said other jaw and the fold-presser.

In testimony whereof, we have hereunto subscribed our names this 31st day of March, 1921.
